230,560

AIR-CARBON ARC CUTTING AND GOUGING TORCH

Kenneth E. McCall and Donald H. Reese, Lancaster,
Ohio, assignors to Arcair Company, Lancaster, Ohio

Filed Feb. 11, 1972, Ser. No. 225,694

Term of patent 14 years

Int. Cl. D8—05

U.S. Cl. D8—98

Fig. 1

Fig. 2

Fig. 3

Fig. 4

FIG. 1 is a perspective view from the left side of the new air-carbon arc cutting and gouging torch.

FIG. 2 is a perspective view taken of the right side of the torch.

FIG. 3 is a top plan view of the new design.

FIG. 4 is a side elevational view of the new design.

The broken line disclosure of a supply hose is for illustrative purposes only.

We claim:

The ornamental design for an air-carbon arc cutting and gouging torch, substantially as shown and described.
